GRINDING WHEEL DRESSER

Fred Edgar Broberg, Racine, Wis., assignor to
 The Dumore Company, Racine, Wis., a corpora-
 tion of Wisconsin

Application August 13, 1938, Serial No. 224,795

9 Claims. (Cl. 125—11)

My invention relates to improvements in grinding wheel dressers.

Where an emery wheel or other grinding wheel is used to grind threads, the periphery of the wheel must be V shaped in cross section. When a new wheel is purchased, the V shaped angle is only approximately correct and the periphery must be ground with a diamond to make it accurate. Also, the periphery must be reground 10 subsequently after a certain amount of use. To accomplish this grinding with sufficient accuracy, the diamond support must be moved in ways or guides arranged at the exact desired angle.

15 The main object of this invention is to provide an improved wheel dresser which may be fitted to any lathe or to a grinding machine.

Another object is to provide an improved wheel grinder so designed that the work need not be re- 20 moved from the machine.

Another object is to provide a device of this character which, after once being set up in a certain lathe, can be removed and when the wheel requires redressing, can be replaced in its exact 25 original location and used without further adjustments.

Certain prior devices provide for adjustment of the diamond support to suit the pitch angle only but they cannot be used to dress the grinder for the tooth shape required of a hob or a worm. 30 A further object of my invention is to provide a device which permits templets to be made to permit dressing of the grinder for any tooth shape, including the types just mentioned.

35 Other objects and advantages will be apparent from a consideration of the following description of a commercial embodiment of the invention.

Fig. 1 is a top plan view of part of a lathe with the present commercial form of dresser attachment mounted thereon;

Fig. 2 is a front elevation of said attachment;

Fig. 3 is a side elevation thereof;

Fig. 4 is a side elevation of the grinder;

Fig. 5 is a front view thereof;

Fig. 6 is a partial end view;

Fig. 7 is a front view of a detail; and

Fig. 8 is a plan view thereof.

The lathe to which the portable dresser is applied may be any standard lathe 10 having the usual ways 11, 11, and other ways 12, 12, spaced 50 farther apart. Part of the head stock 13 is shown as well as part of the tail stock 14. The part to be ground is mounted on the usual centers and is provided in this instance with a conventional, helical thread 15, as shown in Fig. 1. The grinding

wheel 16 has its shaft 17 mounted in a suitable support or quill 18 with a pulley 19 on the other end, driven by means of a belt from a motor, shown also in Fig. 4. The motor and grinder structure are mounted on the tool post carriage 5 or cross slide 20 of the lathe.

The dressing device is provided with a suitable base preferably in the form of overlapping plates 21, 22, which are adjustably held in the desired position by the clamping stud 23, whereby it may 10 slide on the ways 11, 11, of any lathe and may be adjusted in accordance with the distance between said ways. Also, the base is leveled by means of the bolt 24, as shown particularly in Fig. 3. It is clamped to the lathe bed by the nut 25 15 which engages a suitable cross bar in a manner which is well understood, as shown also in Fig. 3.

On said base is mounted a support having the general form of an angle iron 26 with a groove 20 on the rear side which receives a correspondingly shaped portion or slide 27 on the lower end of the vertical support 28, the parts being clamped in adjusted position by studs 29. The support 26 may be slid forward or backward in the groove 30 in the part 22, and clamped in place by studs 25 31. The upright support 28 carries a vertically adjustable, non-rotatable disc 32 on which is mounted a rotatable disc or index plate 33, the graduations thereon being shown in Fig. 1. Said index plate is clamped to the stationary disc by 30 studs or cap screws 34, shown in Figs. 2 and 3. The disc 32 has a pair of diametrically opposite recesses 35 to aid in centering said disc between the lathe centers, as hereinafter explained. The rotatable disc 33 carries a horizontal bracket 36 35 and said disc and bracket may be swung back or forth through a substantial angle, i. e. may be set to any helical angle either left or right hand and held in position.

The bracket 36 has a plate 37 secured thereto 40 as by screws 38, said plate being removable and having a notch therein as shown in Fig. 1. Said plate is called a thread angle templet. Said templet and the discs 32, 33, which support it, are held in the desired vertical position by the stud 39. 45

The templet 37 carries the diamond supporting member 40 which slides in ways 41. The diamond 42 is held in said supporting member by a set screw 43 and said support may be moved back and forth in its guide ways by hand, to dress 50 the periphery of the grinding wheel 16 to the desired angle. As shown in Fig. 1, the grinding wheel when grinding a helical thread, does not rotate in a vertical plane but is inclined somewhat, as shown, to match the threads 15 on the 55

work piece. The ways 41 have a V shaped arrangement corresponding to the desired angle at the periphery of the grinding wheel. A number of templets are available to provide for any thread angle desired, said templets being interchangeable. The grooves in the templet may also be made so as to make it possible to dress the grinding wheel for worm or hob grinding. In either case the dressing of the wheel is accomplished simply by sliding the diamond support 40 back and forth by hand in one groove and then removing it, and using it again in the other of the two grooves.

The base of the portable dresser is provided with a stop or stops 45, as shown in Figs. 1, 2 and 3. The stop is shown in Fig. 1 at the rear of the plate 21, at the right hand side, and is held in an opening therein by a set screw 46, its projecting screw threaded end being provided with a locking nut 47. A corresponding opening is provided in the left hand side of said plate also for a similar stop. It will be noted that the overlapping base plates 21 and 22 are moved to the right as far as possible in Fig. 1, the position of the base being determined by the stop 45 which engages the carriage 20.

In setting up the dressing device, and assuming that there is no work piece mounted in the lathe, the base is placed on the lathe bed. The stationary disc 32 is placed between the lathe centers or conical spindles, which engage the conical recesses 35 and the base plates 21, 22 are then adjusted to the size of the lathe bed and are locked in place by the bolt 23. The height of the front part of the base is then adjusted by means of the bolt 24. After these adjustments, the angle support 26 may be moved forwardly to clear the work piece which is to be mounted in the lathe. Assuming that the grinder has already been mounted on the lathe, with the carriage 20 in approximately the correct position, the base of the dresser must be in a position which will permit the grinding wheel to enter the V-shaped notch in the templet, and this position is attained by the various adjustments permitted by the angle support 26, the fine adjustment being attained by the stop 45 when properly adjusted to engage the carriage 20. The thread angle templet is then adjusted to the desired helical angle, left or right, and assuming that the grinding wheel is a new one requiring dressing, this truing of the grinding surface may now be readily accomplished.

It will be noted that the thread angle templet and associated parts are located between the work and the grinding wheel. Therefore, it is not necessary to remove the work from the lathe centers during the grinding operation either initially or subsequently. The dressing device may readily be lifted from the lathe bed by loosening the nut 25 and when it is necessary to remount the same on the lathe bed a little later, this may readily be accomplished, and the dresser moved to the right until it engages the carriage 20, at which point the regrinding operation may take place with assurance that the relative positions of the grinder, the templet and the diamond will be exactly the same as before. Since the carriage 20 travels along the ways of the lathe during the grinding of the thread by the grinding wheel, said carriage may be stopped in any one of a number of different positions, but whatever its position of rest, the base of the grinder, when the latter is in use, will always be positioned against said carriage and thus maintain the rela-

tive position of the device in relation to the feed screw. The stop or stops 45 will also be used when changing from one pitch to another so as to insure that the wheel will be dressed symmetrically with respect to its center line.

It will also be noted that the dressing device need not necessarily be removed from the lathe but if the work piece permits, the grinding wheel may be moved away from the templet to clear the latter and then the templet slid to the left (i. e. toward the head stock) out of the way of the grinder, and the latter moved back to grinding position.

In addition to the obvious advantages of this dresser attachment it will be seen that the indexing discs are located on exact center so that the wheel will be correctly ground, even though it is slightly off center. The dressing device is stationary on its base after being adjusted and in being used the grinding wheel is brought up to the dresser unit rather than moving the dressing unit to the grinding wheel, the latter being mounted to utilize a lathe compound permitting this movement. Also, the grinding spindle has a vertical adjustment so as to fit any normal lathe. The design of the dresser parts is such that there is no chance of errors from adjustments. The dresser base and the grinder base are independent, so that the former may be made to fit any lathe.

The dresser can be fitted to any lathe or to certain types of grinding machines merely by changing the effective length of the overlapping base plates or by replacing one of them with a longer plate where the limits of the base shown in the drawings, are exceeded.

The grinder, as previously stated, is supported on the carriage 20, by a supporting plate (Fig. 4) forming part of an angle plate, the upper flange of which is indicated at 48. The vertical plate 48 has mounted behind it additional adjustable plates 49 and 50, as shown also in Figs. 5 and 6. The plate 50 carries a boss 51 which supports the bracket 52 on which the motor 53 is mounted. The purpose of said adjustable plates is to permit the motor shaft to be swung about a certain axis of rotation, to tilt the grinding wheel or disc out of a vertical plane into some predetermined inclined plane, as hereinafter described. The motor drives the pulley 19 by a belt 54.

On the rear of the supporting plate 48 is an arc shaped groove 55 which receives a correspondingly curved rib 56 on the front of the plate 49, which is shown more fully in Figs. 7 and 8. The opposite end of said plate is curved at 57, and has screw threaded openings 58, 59 therein to receive studs 60, 61, slidable in the curved slots in plate 48, shown in Fig. 5. By this means the plate 49 may be clamped in any desired position of angular adjustment with respect to a horizontal axis passing through the edge of the grinder and intersecting the axis of the shaft on which it is mounted.

Said plate 49 has two additional screw threaded openings 62, 63 therein to receive the studs 64, 65, which permit vertical adjustment of the plate 50 to the rear of the plate 49. Said studs pass through vertical slots 66 in the rear plate 50. Said rear plate is guided in its up and down movement by a slot in the rear face of the plate 49, which slot receives a rib 68 on the rear plate 50, as shown in Fig. 1.

The curved end of the front plate 48 has graduations 69 thereon representing circumferential degrees, to aid in adjusting the plate 49 rotatively.

Such rotation, it will be noted, also swings the entire motor structure and its supporting parts, through a predetermined angle for the purpose of swinging the grinding wheel out of a vertical plane into the desired inclined plane so that said wheel may grind at the same helical angle as that to which the dressing device is set. For this purpose the graduations 69 in Fig. 6 correspond to those shown on the dressing device in Fig. 1.

In setting up the grinder the parts 48 and 49 are first locked together in the zero position, as in Fig. 6. The part 48 is then fastened to the lathe compound with the usual T bolt and nut. The frame of the grinder is then mounted on the boss 51 and secured in position. The shaft 17 of the grinding wheel is then mounted between the lathe centers to hold it in the proper position while the vertical adjustment is accomplished by means of the cap screws 64, 65. If the lathe is of such a size that the slots 66 are too short to permit the desired adjustment, parallel bars are inserted between the lathe compound and the base 41, to give the rough adjustment, the said slots and cap screws providing for the finer adjustment. The grinder is then removed from the centers and backed up to be adjusted to whatever helical angle is desired, by loosening the cap screws 60, 61, swinging the grinder structure and its supporting parts to the desired angle and then locking the parts in position. It will be noted that while this helical angle adjustment is being made, the plates 49, 50 and the parts supported thereby are held by the curved rib 56 which engages its slot 55 in the part 48.

While I have shown and described one embodiment of my invention, it is to be understood it is capable of many modifications. Changes, therefore, in construction and arrangement may be made without departing from the spirit and scope of the invention as disclosed in the appended claims.

I claim:

1. The combination with a lathe having a tool post carriage, of a grinding wheel mounted on said carriage, a wheel dresser comprising a base having two relatively adjustable members arranged to slide on the ways of said lathe, means for securing said base to said ways, an upright support on said base and a thread angle templet vertically adjustable thereon.
2. A device as in claim 1 with the addition of means for adjusting one side of said base vertically with respect to said ways.
3. The combination with a lathe having a tool post carriage, of a grinding wheel mounted on said carriage, a wheel dresser comprising a base having two relatively adjustable members arranged to slide on the ways of said lathe, means

for securing said base to said ways, an upright member slidably mounted on said base to permit adjustment back and forth thereon, a fixed plate on said upright member, an index plate rotatably secured to said fixed plate and a templet on said index plate having V grooves therein to support and guide a diamond holder. 5

4. A grinding wheel dresser as in claim 3, with means for adjusting said upright member with respect to said two-part base, in a direction parallel to the ways of the lathe. 10

5. A portable dresser comprising a base adjustable along the ways of a lathe, a vertical standard adjustable on said base both longitudinally and transversely, a thread angle templet 15 vertically adjustable on said standard and an adjustable stop on said base to engage the lathe carriage and insure the same location of said base with respect to said carriage and the feed screw therefor when said dresser is removed from 20 said lathe and subsequently restored thereon.

6. A portable dresser comprising a base adjustable to the ways of lathes of different sizes, a vertical standard adjustable thereon both longitudinally and transversely, a vertical plate adjustable in ways on said standard, a second plate 25 rotatably mounted on said first plate and a templet support on said second plate.

7. In a grinding wheel dresser, a base, a vertical member thereon having a horizontal groove 30 therein, a vertical standard having a rib thereon fitting said groove and means for clamping said standard to said member in adjusted position horizontally, a plate having an extension slidable vertically on said standard, means for clamping the same at the desired height, said plate having recesses on opposite sides to permit centering in a lathe, a second plate rotatably mounted on said first plate in contact therewith, a stud and slot connection to adjust said second plate to the desired helical angle of the thread to be ground, and a third plate having V grooves therein removably secured to said second plate. 35

8. A grinding wheel dresser as in claim 7, with the addition of a diamond holder slidable in said 40 grooves.

9. A portable dresser comprising a base slidably mounted on the ways of a lathe, a vertical standard adjustable both longitudinally and transversely on said base, a thread angle templet 50 vertically adjustable on said standard and a stop on said base to engage the lathe carriage and insure the same location of said base with respect to said carriage and the feed screw therefor when said dresser is removed from said lathe 55 and subsequently restored thereon, regardless of the position in which said carriage may come to rest.

FRED EDGAR BROBERG.
